FREQUENCY DEPENDENT DAMPING
NETWORK

Holger Lueder, Berlin-Friedenau, Germany, assignor to Siemens & Halske Aktiengesellschaft, Siemensstadt, near Berlin, Germany, a corporation of Germany

Application February 20, 1937, Serial No. 126,786
In Germany February 22, 1936

10 Claims. (Cl. 178—44)

It has already been proposed to produce frequency-dependent damping networks wherein coils or condensers are inserted in the series and/or parallel train of networks. However, these arrangements have the disadvantage that the inductive resistance of coils, and the conductance of condensers increase in direct proportion with the frequency of the alternating currents passing therethrough. In many cases, in order to reduce distortion, it would be of advantage to employ electric networks with resistance elements whose dependence on frequency is non-linear. In this way with networks of very simple construction results could be obtained such as can today only be achieved with coils, condensers and frequency independent resistances most of which are required to be of unwieldy size and are, therefore, of costly construction.

20 My invention will be explained in further detail, reference being made to the accompanying drawing, in which

Figures 1, 2, 3, 4 and 12 show, respectively, different filter characteristics by which the theory underlying my invention is explained;

25 Figs. 5 to 10 inclusive show, respectively, different embodiments of a filter network in accordance with my invention; and,

Fig. 11 illustrates a further modification of 30 my invention in which a temperature-dependent resistance is preferably employed.

In accordance with the invention it is proposed to provide a simple filter system in which distortion is minimized. The invention is particularly adapted to the reduction of distortion in telegraph lines. It is based upon the teaching that, as shown in Fig. 1, a resistance with a negative temperature coefficient whose current-voltage characteristic has a horizontal course (curve 35 1) offers a negligible impedance to alternating currents passed across the resistor at a preliminary load according to the current I_g , if the frequency of the alternating current is very low, but in case that alternating currents of higher frequency operate in the working point, an alternating current resistance is produced which corresponds to the lines 0—2 in Fig. 1. Theoretically this value appears only at infinitely high frequencies, but in practice this value will be reached in ordinary hot conductors at frequencies of the order of several kilocycles. In the region of transition a dynamic characteristic of elliptic shape is obtained (curve 3 of Fig. 1). When using other preliminary load currents, for 40 instance, I_g' or I_g'' , alternating current resist-

ance will be obtained at high frequencies in accordance with the inclination of the lines 0—4 and 0—5.

Fig. 2 shows the approximate course of the alternating current resistance of a hot conductor 5 in accordance with Fig. 1 at an increase in frequency. The alternating current resistance R at first increases with an increase in frequency f , and then approaches asymptotically the end value R_2 determined by the inclination of the line 10 0—2 (Fig. 1). As shown in Fig. 2, the resistance increases only approximately in proportion to the root of the frequency of the telegraph currents, except as already pointed out, that it approaches asymptotically a finite value.

15 In the Figs. 3 and 4 corresponding conditions are represented for temperature dependent resistance with highly positive temperature coefficient. If, in this case, in accordance with Fig. 3, a static characteristic is used, namely, one in 20 which the voltage characteristic takes a horizontal course, then as shown in Fig. 4, the conductance G of such resistance, in the same manner as the resistance of the hot conductor according to Fig. 1 and Fig. 2, takes the same course as the 25 resistance of a hot conductor according to Fig. 2.

20 On the basis of the teaching just described it is proposed, in accordance with the invention, to produce frequency dependent damping networks 30 applicable with advantage for various technical purposes, in that temperature dependent resistances are connected in series and/or parallel branches with effective resistances, and that the working point of the temperature dependent resistances is so chosen that a desired dependence 35 on frequency of the damping network is obtained. Especially suited for this purpose are temperature dependent resistances whose characteristic traced at direct current (static characteristic) reveals a constant voltage or a constant 40 current within a wide range.

45 In order to illustrate the possibilities for employing temperature-dependent resistances in a manner required for carrying out my invention it should be mentioned that a number of materials have been experimented with and among them the following have been found useful: uranium dioxide, chromium oxide, molybdenum dioxide, titanium oxide and zirconium oxide. The particular materials just mentioned fall within the 50 group of non-linear resistances having a negative temperature coefficient. They are sometimes referred to as hot conductors as contrasted with so-called cold conductors having a positive temperature coefficient. It should be understood also 55

that the resistance temperature characteristic of the material that is used is to some extent determined by the dimensions and the shape of the element which is formed into a resistor.

- 5 A number of different embodiments of my invention are shown in Figs. 5 to 11 inclusive. These figures show different arrangements of resistance units connected in the series and parallel branches respectively of a filter system. Each of 10 the filters shown has input terminals on the left and output terminals on the right of the diagram. It will be understood that any suitable load is connected to the output terminals. In each of these figures the resistance unit designated W 15 is one which has a substantially zero temperature coefficient. The resistance H, on the other hand, has a negative temperature coefficient and is sometimes termed a hot conductor. The resistances designated K are cold conductors or resistance units having a positive temperature coefficient.

Due to the disposition of these resistors in the arrangements of Figs. 5, 6 and 7, all of the filters therein shown are high pass filters. Thus, in 20 Fig. 5 the resistor W having a substantially zero temperature coefficient is placed in the series arm, while the resistance H having a negative coefficient is placed in a parallel arm of the filter. In Fig. 6 a cold conductor having a positive temperature coefficient is in one of the series arms, while a resistance W having a substantially zero temperature coefficient is placed in a parallel arm. In Fig. 7 the arrangement is similar to that of Fig. 6 except that a hot conductor having a negative 25 temperature coefficient is substituted for the resistor W of Fig. 6 in the parallel arm.

Low pass filters are represented in each of the embodiments shown in Figs. 8, 9 and 10. Here the resistor H of Figs. 8 and 10 is placed in a series arm and a resistor W as in Fig. 8, or a resistor K as in Figs. 9 and 10, is placed in a parallel arm. It will be remembered that the resistor W has a substantially zero temperature coefficient, while the resistor K is a cold conductor having a positive temperature coefficient. In Fig. 9 45 the resistor W is placed in a series arm of the filter.

Fig. 11 shows another high pass filter which 50 comprises a resistor W having a zero temperature coefficient and a resistor H having a negative temperature coefficient, both of these resistors being placed in a parallel arm and in series with one another. The resistor H, however, is preferably shunted by a circuit which includes a choke D, a direct current source B and an adjustable 55 potentiometer R'. The utility of this shunt circuit around the resistor H will now be explained.

In order to be able to set the working point of the temperature dependent resistances in the desired manner, a variable bias potential or a variable 60 preliminary current is applied in the known manner to the temperature dependent resistances. This bias potential is supplied by the battery B. The choke is preferably inserted for the purpose of avoiding an alternating current short 65 circuit through the battery. The value of the bias potential is controlled by the adjustment of the potentiometer R'. According to the arrangement shown in Fig. 11 the circuit or device whose internal resistance is to be compensated 70 is designated W'. This unit may be either a generator or a telegraph line or any other unit which is subject to variations of its impedance due to frequency variations. In such cases the parallel arm of the filter is effective to reduce distortion. 75 In the same manner the preliminary current or

bias voltage can be controlled in the other arrangements shown in Figs. 5 to 10.

The arrangements according to the invention can be utilized with particular advantage for the reduction of distortion in telegraph lines. The damping increase in telegraph lines, especially in 5 telegraph cables, has a characteristic that is approximately inversely proportional to the damping increase of a high pass filter constructed by the elements proposed in accordance with the 10 invention.

When negative resistances are inserted in telegraph lines or cables for the purpose of damping reduction, then it is with particular advantage that the temperature dependent resistances of my invention may be employed. This is true because there are certain indeterminate components of the resistors having a negative temperature coefficient which can be utilized in a compensating manner for the reduction of distortion. The high 15 pass filter shown in Fig. 11 illustrates a preferred system to be so employed. The ohmic resistor W prevents a short circuit of the low frequencies which are fed to the line or cable. Such a short circuit is otherwise substantially 20 offered at low frequencies by the hot conductor H having a negative temperature coefficient.

By the choice of the material, the dimensioning of the hot conductors, as well as by the choice of the most favorable working point and by the proper dimensioning of the series resistances W, 25 it is always possible to easily obtain a distortion reducing network which is matched to a wide degree with the damping curve (b) of the cable. Fig. 12 shows, by way of example, the damping 30 curve of a Pupinized telegraph cable P and the conductance G of a high pass filter constructed in accordance with the invention. It is found that in the entire range required for the transmission of audible speech currents both curves have practically 35 the same course.

I claim:

1. In circuit with a load having a non-linear frequency-response characteristic, a frequency dependent damping network comprising a plurality of temperature-dependent non-reactive resistors in series and parallel branches of said network, and means for so adjusting the resistance-temperature characteristic of at least one of said resistors that said network possesses a desired damping characteristic dependent upon 45 frequency variations of the energy impressed thereon.

2. A network in accordance with claim 1 and further characterized in that the stationary current-voltage characteristic of the temperature dependent resistor follows a substantially horizontal course within a predetermined range of frequencies.

3. A frequency dependent damping network in accordance with claim 1, and having at least one of the resistors of said network such that it possesses a negative temperature coefficient.

4. A high-pass filter system having a plurality of series and parallel disposed impedances, one 65 of said impedances being a temperature-dependent resistance having a positive temperature coefficient and disposed in the series train, another of said impedances having a resistive characteristic substantially independent of temperature 70 and disposed in the parallel train of said network, and means for so adjusting the working point of the temperature-dependent resistance that a desired high-pass characteristic is obtained in said filter system.

5. A frequency dependent damping network having series and parallel branches, characterized in that non-reactive temperature dependent resistances are connected together with effective resistances in at least one of said branches, and that the working point of the temperature dependent resistances is so chosen that a desired dependence on frequency of the damping network is attained.
10. 6. A network according to claim 1 characterized in that the stationary current-voltage characteristic of the temperature dependent resistance is substantially linear within the operational range of said characteristic.
15. 7. A damping network comprising a series resistor, a parallel resistor, input terminals connected to a variable frequency alternating current source, and output terminals connected to a load having a variable frequency response characteristic, at least one of said resistors having a relatively high temperature coefficient and a frequency-dependent damping characteristic and being relatively non-reactive.
8. A damping network according to claim 7 wherein one of said resistors possesses a useful negative temperature coefficient and the other of said resistors possesses a substantially negligible temperature coefficient.
9. A damping network according to claim 7 wherein the parallel resistor possesses a higher negative temperature coefficient than that of the series resistor, whereby a high-pass filter characteristic is obtained in said damping network.
10. A damping network according to claim 7 wherein the series resistor possesses a higher negative temperature coefficient than that of the parallel resistor, whereby a low-pass filter characteristic is obtained in said damping network.

HOLGER LUEDER. 20
